CLAIM

We claim the ornamental design for a sample holder, as shown and described.

DESCRIPTION

This invention was made with government support under grant number CA206937 awarded by the National Institutes of Health. The government has certain rights in the invention.

FIG. 1 is a perspective view of a sample holder according to the claimed design;

FIG. 2 is a side view of the sample holder of FIG. 1;
FIG. 3 is another side view of the sample holder of FIG. 1;
FIG. 4 is a front view of the sample holder of FIG. 1;
FIG. 5 is a rear view of the sample holder of FIG. 1;
FIG. 6 is a top view of the sample holder of FIG. 1;
FIG. 7 is a bottom view of the sample holder of FIG. 1; and,
FIG. 8 is another perspective view of the sample holder of FIG. 1.

The broken line immediately inside the claimed circular feature shown in FIG. 7 depicts the boundary of the claim and forms no part thereof. The rest of the broken lines in the drawings depict environmental subject matter and form no part of the claimed design.
